UNITED STATES PATENT OFFICE.

HUGO PRAHL, OF DUSSELDORF, GERMANY, ASSIGNOR TO RHEINISCHE METALL-WAAREN- UND MASCHINENFABRIK, OF DUSSELDORF-DERENDRÖF, GERMANY, A CORPORATION OF GERMANY.

CLOCKWORK-ESCAPEMENT ESPECIALLY APPLICABLE TO MECHANICAL TIME-FUSES.

1,148,402.

Specification of Letters Patent.

Patented July 27, 1915.

Application filed January 14, 1914. Serial No. 812,096.

To all whom it may concern:

Be it known that I, HUGO PRAHL, a subject of the German Emperor, residing at 14 Moltkestrasse, Dusseldorf, Germany, have 5 invented certain new and useful Improvements in Clockwork-Escapements Especially Applicable to Mechanical Time-Fuses; and I do hereby declare the following to be a full, clear, and exact description of the invention, such as will enable others skilled in the art to which it appertains to make and use the same.

The present invention relates to clockwork escapements, intended for mechanical time 15 fuses, of the kind in which two sets of pins, teeth or the like arranged in two circles of different diameter, the teeth of one set being staggered with respect to those in the other, are adapted to coöperate with an anchor arranged 20 operatively between the two sets.

The present invention differs from the known constructions of this kind, in that the anchor constructed as a segment of a circle is journaled between the rows of pins in 25 such a manner that the cylindrical part of the periphery of the anchor coöperates, in both directions of its swing, with a pin to form a stop for the escapement wheel.

One construction of the invention is illustrated in the accompanying drawings in which—

Figure 1 shows the escapement in section, while Fig. 2 is a plan view. Figs. 3 and 4 show the escapement wheel carrying the 30 teeth or projections and the anchor in two different positions.

The axis *f* of the segmental anchor *E* is journaled in the plate *a* and a bridge piece *b*, and is made solid instead of hollow as are 40 the cylinders of previous known escapements. Between the plate *a* and a second plate *c* the escapement wheel *D* is journaled and the latter is provided with two rows of pins *d'* and *d''*, the pins *d'* forming 45 a smaller or inner circle and pins *d''* a larger or outer circle on the wheel, the two groups of pins breaking joint with each other, that is to say they are on different radii of the circles. The escapement wheel 50 *D* is driven in the direction of the arrow *g* by means of a spring or other suitable means not shown. The balance spring actuating

the anchor *E* is omitted from the drawings for the sake of clearness. In its normal position, that is to say, when it is not subjected to any strain, it holds the anchor in the position shown in Fig. 3. As soon as the escapement wheel strikes with pin *d'* on the portion *e'* of the flat face of the anchor *E*, the latter is turned in the direction of the arrow *h* (Fig. 4) until the pin *d'* slides past and off the flat face; at this moment the pin *d''* commences to bear against the cylindrical face of the anchor, thus stopping the wheel *D*. The anchor *E* turns a little further 55 owing to its momentum until this is overcome by the regulating spring, whereupon the anchor swings back. Owing to this the pin *d''* strikes the portion *e''* of the flat surface of the anchor and imparts to it a fresh 60 impulse in the direction opposite to the arrow *h*, until the pin *d''* in turn slides off the surface *e''*. At this moment the next pin *d'* arrives against the cylindrical face of the anchor and so brings the escapement wheel 65 *D* again to rest. After the commencement of the return swing of the anchor the pin *d'* bears on the surface *e'* (Fig. 3) and the movement is repeated.

If the escapement is to be constructed as a recoil escapement, it is only necessary to mount the anchor *E* with its circumference eccentric to the pivot *f* as the dotted segment *i* in Fig. 4 indicates.

I claim as my invention:

1. A clockwork escapement adapted for mechanical time fuses comprising an escapement wheel, inner and outer series of projections on said escapement wheel, arranged on different radii, and an anchor pivotally mounted within the path of said projections, said anchor having a flat edge and a rounded edge with which said projections alternately contact, said rounded edge forming a stop for said escapement wheel when a projection of either set contacts therewith.

2. A clockwork escapement adapted for mechanical time fuses comprising an escapement wheel, inner and outer series of pins projecting from said wheel, the two series 100 of pins being on different radii, and an oscillatory anchor of segmental form axially mounted adjacent to said escapement wheel, the axis of said anchor being between the

circles described by said pins in the revolution of said wheel, said segment having a rounded edge and a flat edge with which edges the pins of the two series alternately engage, said rounded edge forming a stop for said escapement wheel, when the projection of either set contacts therewith.

In testimony whereof, I have signed this specification in the presence of two subscribing witnesses.

HUGO PRAHL.
